GARRISON BABCOCK, OF ROCHESTER, NEW YORK, ASSIGNOR TO TELECHRONOMETER COMPANY, OF ROCHESTER, NEW YORK, A CORPORATION OF NEW YORK.

TELEPHONE METERING SYSTEM.

1,019,879.

Specification of Letters Patent. Patented Mar. 12, 1912.

Application filed June 6, 1910. Serial No. 565,192.

To all whom it may concern:

Be it known that I, GARRISON BABCOCK, a citizen of the United States, residing at Rochester, in the county of Monroe and 5 State of New York, have invented a certain new and useful Improvement in Telephone Metering Systems, of which the following is a full, clear, concise, and exact description, reference being had to the accompanying drawings, forming a part of this specification.

My invention relates to an improvement in telephone metering systems in which apparatus at a central exchange is adapted to 15 be associated with the connecting mechanism of the exchange in use to connect subscribers for conversation so as to actuate a registering mechanism at the exchange in accordance with the rate to be charged for 20 service to the calling subscriber. The mechanism employed to thus register the charge is adapted, when released by the operator, to send suitable impulses through the line wires of the calling subscriber to actuate 25 metering mechanism located at the substation of the latter to effect a charge on the calling subscriber's meter corresponding to the amount registered by the apparatus at the central exchange.

30 In carrying out my invention I designate the unit of telephone service used in connection with the registering mechanism at the exchange as a telechrone, which signifies an amount of service consisting of both a 35 time element and the charge per unit of time, which is different for different subscribers, depending upon the distance they are from the exchange. Thus the service expressed in telechrones may in two different 40 cases be the same, although produced by different factors of time and charge rate.

The several drawings illustrating my invention are as follows:

Figure 1 is a diagrammatic drawing, 45 illustrating the circuit connections involved between a calling and a called subscriber together with the connecting circuits employed at a central exchange for establishing telephonic communication between such 50 subscribers; Fig. 2 is an enlarged diagrammatic view of the mechanism employed for effecting different rates of operation of the registering mechanism at the exchange;

Fig. 3 is a detail view of the connecting keys employed to control the receiving and 55 sending operations of the registering mechanism at the exchange; Fig. 4 is a detail view of the mechanism employed to actuate the registering mechanism at the exchange; Fig. 5 is a detail view of the mechanism associated with the register at the exchange for causing its operation to send the charge made upon such register through the calling line to actuate the meter at the calling subscriber's station; Fig. 6 is an 60 enlarged detail view of the operating mechanism of the meter located at the subscriber's station.

As shown in Fig. 1, the substation A is provided with a transmitter 1 and receiver 2 in the manner well known in the art, and also with a switch hook 3 adapted to either close the line circuit through the transmitter 1 or through the ringer 4, depending upon whether the receiver 2 is removed from the 75 hook or is located upon it. The circuit extending from the transmitter 1 is continued through the energizing coil 5 of the subscriber's metering mechanism 6. Substation A is connected with the exchange by line 80 wires 8 and 7 terminating in the tip and sleeve springs 9 and 10, respectively, of the jack J, the ring 11 of which is connected with the winding of the cut-off relay 12, the other terminal of which is connected 85 with the battery 13 through the conductor 14. The conductor 14 is also connected with one terminal of the line relay 15 and with the pivotal point of the armature of such relay, as a result of which, when the hook 90 3 occupies its upper position due to the removal of the receiver 2, the line relay 15 is energized and the line signal 17 is lighted. When the subscriber at the substation A desires to call central the relay 15 is energized, 95 since for this condition the cut-off relay 12 is inert and connection is established at this time between the line wires 7 and 8 and conductors 16 and 14 with the terminals of the battery 13. The armature 100 of the relay 15 in its attracted position lights the line lamp 17, thus signaling the operator that a connection is desired. The substation B is connected with the exchange by line wires 18 and 19 which have associated with them apparatus similar to that 105

described above for the line 7, 8. The line wires 18 and 19 are connected with the tip and sleeve springs 20 and 21 of the jack J¹.

The cord circuit employed in connection 5 with my invention consists of an answering plug P and a calling plug P¹ connected by tip strand 22, 23 and sleeve strand 24, 25, the sections of each strand being separated by condensers as indicated. The sections 22 10 and 24 of the cord strands are connected through supervisory relays 26 and 27 with the conductors 28 and 16 respectively, and thus with the terminals of the battery 13. The sections 23 and 25 of the cord strands 15 are connected by the wires 29 and 30, with the windings of the supervisory relays 31 and 32 and thus with springs 33 and 34 of the switch K. The inner springs 35 and 36 of the switch K, which are normally in contact with the springs 33 and 34, respectively, 20 are connected with the terminals of the battery 13, the path from the spring 35 being through wires 37 and 28, while the path from the spring 36 is closed through wires 38 and 39. The outer springs 40 and 41 of the switch K are connected through wires 25 42 and 43 with the outer and inner switch springs, respectively, of the reversing switch mechanism K¹. An electromagnet 44 30 is located in the wire 42, as indicated, for a purpose to be described, the connection to the springs of the switch K¹ being completed from such electromagnet through wire 45. The sections 23 and 25 of the cord 35 strands are completed through the ringing key K² by means of which the ringing generator 46 may be connected in circuit with the calling plug P¹ to signal the called subscriber. The operator's set 47 may be connected 40 with the sections 22 and 24 of the cord strands when desired by means of the listening key K³. The back contact 47 of the supervisory relay 31 is connected with the front contact 48 of the supervisory relay 45 32 through the supervisory lamp 49, and the front contact 50 of the supervisory relay 31 is connected by wire 51 with the normally open contacts 52, 52^a, 52^b, 52^c, 53, 53^a, 54, 55, 56 and 57 adapted to be connected by 50 corresponding switches 58, 58^a, 58^b, 58^c, 59, 59^a, 60, 61, 62, 63 with brushes bearing upon the commutators 64, 64^a, 64^b, 64^c, 65, 65^a, 66, 67, 68, 69, as desired. The commutators 64, 64^a, 64^b and 64^c are carried upon a shaft 70 55 driven by means of gears 71 and 72 from a shaft 73 driven by means of suitable gearing from time-controlled mechanism not shown so that such shaft 73 will rotate at a uniform rate. The commutators 65 and 65^a 60 are mounted upon a shaft 74, which is driven from the shaft 73 by suitable gearing at a rate different from the rotation of the shaft 70. Commutators 66, 67, 68 and 69 are mounted upon shafts 75, 76, 77 and 78, 65 which are individually driven from the

shaft 73 by suitable gearing at rates different from each other and from the rate of rotation of the shafts 70 and 74. The body portions of the commutators referred to are electrically connected with the shafts carrying them and the shaft 73 is connected by spring 79 with one terminal of the winding of the electromagnet 80, the other terminal of which is connected by a wire 81 with wire 37, and thus through wire 28 with one terminal of the battery 13. The electromagnet 80 is provided with an armature 82 pivoted at 83, which armature has pivotally connected to its right-hand end a spring pawl 84 so disposed relatively to a fixed stop 85 that when the armature 82 is attracted the pawl 84 is first moved into engagement with the ratchet wheel 86 and then operates to rotate such ratchet wheel and the shaft 87, to which it is secured, one step. A pawl 88, 85 pivoted at 89, is normally held in engagement with the ratchet wheel 86 by a spring 90 to retain the ratchet wheel in the position to which it is moved by the operating pawl 84. When the magnet 80 is deenergized a 90 suitable spring 91 returns the armature 82 to its normal position, for which position the pawl 84 is moved entirely out of the path of the ratchet wheel 86. The shaft 87 has secured thereto a gear 92 meshing with a gear 93 carried by a shaft 94, which latter shaft carries a threaded portion 95 engaging a nut 96 adapted to be moved longitudinally of the shaft 94 by its rotation, while rotation of the nut 96 is prevented by suitable 100 means not shown. The right-hand end of the shaft 94 carries a disk 97, shown more clearly in Fig 5, and to this disk one end of a spring 98 is secured, the other end of such spring being connected with the framework of the registering mechanism. The disk 97 also carries a spring pawl 99 adapted to engage a ratchet wheel 100, which is independent of the disk 97 and shaft 94, but is adapted to be rotated by such disk when 105 the same is moved in a direction to move the nut 96 to the left, as shown in Fig. 1. The ratchet wheel 100 has projecting therefrom a stud 101 of insulating material adapted to engage the cam 102 carried by one 110 of the operating springs of the switch K¹.

The switch K¹ consists of two operating springs 103 and 104 connected together by a block of insulating material 105. The spring 103 is connected by wire 106 with the armature 107 of the magnet 44 and also by wire 108 with the contact 109. The spring 104 is connected by wire 110 with a pilot lamp 111, the other terminal of which is connected with the contact 112 adapted to be 120 engaged by the armature 107 when the magnet 44 is deenergized. The spring 104 is also connected by wires 38 and 39 with one terminal of the battery 13. The springs 103 and 104, when in their normal position 130

shown in Fig. 1, are in contact with the springs 113 and 114 connected with the wires 45 and 43, respectively, and when the switch K^1 is operated by means of the stud 101 and 5 the cam 102 the operating springs 103 and 104 are moved from engagement with the springs 113 and 114 and into engagement with the springs 115 and 116, which are connected respectively with the wires 43 and 10 45. Thus, as will be seen in connection with the operation of the mechanism as will be described below, the switch K^1 constitutes a reversing switch and serves to reverse the direction of current flow through the line 15 with which the plug P^1 is connected.

The nut 96 when in its normal position, by means of a projecting arm 117 carried thereby, engages a spring 118 to prevent it making contact with the spring 109 and thus 20 serves to interrupt connection between the wire 37 and the wire 108. When the nut 96 is moved from its normal position by the operation of the magnet 80, the spring 118 engages the spring 109, thus serving in 25 part to close the circuit controlled by the switch K^1 .

The key K serves, when in its normal position to close the circuits of the supervisory relays 31 and 32 when the switch hook 30 at the connected substation is in its talking position, and when the switch K is moved to its alternate position this circuit is interrupted and a circuit is established from the battery 18 through the reversing switch K^1 35 to the calling plug P^1 for a purpose to be described. The switch K and the switches 58, 58^a, 58^b, 58^c, 59, 59^a, 60, 61, 62 and 63 are assembled upon a common frame, as indicated in Fig. 3, and are provided with a 40 latch plate 119 which retains any one of the operated keys in its actuated position until another of such keys is operated, the operation of the second key serving to release the locking cam carried by the first key.

45 The commutators driven by the shaft 73 are shown more in detail in Fig. 2, and as a result of the gearing employed and the number of segments in these commutators, they may advantageously be arranged to 50 close the circuit through the magnet 80 as follows: The commutators 64, 64^a, 64^b and 64^c may consist of 4, 5, 6 and 12 segments, respectively, and the shaft 70 may be driven so as to make one rotation per minute, as a 55 result of which the commutators mentioned will effect a closure of the energizing circuit through the magnet 80 once every fifteen seconds, once every twelve seconds, once every ten seconds, and once every five seconds, respectively; the commutators 65 and 65^a may have four and eight segments, respectively, and by proportioning the gearing between the shaft 73 and the shaft 74 60 so that the latter shaft is rotated once in fifty-six seconds, the commutators will close

the energizing circuit of the magnet 80 once in fourteen seconds and once in seven seconds, respectively; the commutators 66 and 67 may each consist of four segments and the shafts 75 and 76 may be driven so as to 70 make one rotation every fifty-two seconds and every forty-four seconds, respectively, thus energizing the electromagnet 80 once every thirteen seconds and once every eleven seconds, respectively; the commutators 68 75 and 69 may consist of eight segments each and the shafts 77 and 78 may be rotated by means of the gearing between them and the shaft 73, so as to make one rotation in seventy-two seconds and sixty-four seconds, 80 respectively, thus closing the energizing circuit of the electromagnet 80 once every nine seconds and once every eight seconds, respectively. Thus means are provided by the closure of the proper one of the keys connected with the commutator described to 85 close the energizing circuit through the magnet 80 once in six, seven, eight, nine, ten, eleven, twelve, thirteen, fourteen or fifteen seconds, as desired, the intervals between 90 successive closures of the circuit being determined by the rate charged for telephone service to the subscriber making the call, which rate may be determined by the distance the subscriber is from the exchange or 95 the nature of the service offered such subscriber. It is to be understood that any desired rate of operation of the magnet 80 may be secured by mechanism similar to that just described.

The metering mechanism 6 located at the substation A is constructed as indicated in Fig. 6 and consists essentially of a permanent magnet 120 to which is pivotally connected at 121 an armature 122 carrying a 105 coil 5, which coil is located in a block of soft iron 124 carried by the lower pole of the magnet 120, the block 124 being recessed to receive the coil 5. The coil 5 is connected in circuit with the transmitter 1 and the line wire 7, as indicated in Fig. 1, and thus serves to move the armature 122 in one direction or the other, depending upon the direction of current flow through the coil 5. The metering mechanism is actuated, as indicated in Fig. 1, by means of suitable pawl and ratchet mechanism connected with the armature 122.

110 The operation of my invention is as follows: Assuming that the subscriber at the substation A desires to converse with the subscriber at substation B, the receiver 2 is removed from the switch hook 3 and the line signal 17 is illuminated as a result in a manner well known in the art. The current flow through the line wire 7 at this time is in a direction to attract the armature 122 of the metering mechanism 6 and thus to place the registering mechanism of the meter 6 in condition to be actuated. The opera- 115

tor at the exchange, in response to the signal produced by the line lamp 17, inserts the plug P into the jack J, thus establishing the following circuit from battery 13: battery 13, wire 14, cut-off relay 12, ring 11 of the jack J, sleeve strand 24, supervisory relay 27, wire 16 back to battery 13. Thus the cut-off relay 12 is energized and connection between the wires 14 and 16 and the line conductors 8 and 7 is interrupted. The coil 5 is maintained energized, however, by current flowing over the following path: battery 13, wire 16, supervisory relay 27, cord strand 24, sleeve spring 10, line wire 7, coil 5, transmitter 1, switch hook 3, line wire 8, tip spring 9, tip strand 22, supervisory relay 26, wire 28, wire 14, back to battery 13. The operator, by depressing her listening key K³, ascertains the connection desired and at the same time depresses one of the rate keys 58, 58^a, 58^b, 58^c, 59, 59^a, 60, 61, 62, 63, depending upon the rate that is charged subscriber A for service, or upon the rate that is to be charged him for the connection desired. For example, he may desire a long distance connection, the rate of which is determined by the location of the subscriber B relatively to the exchange and the rate charged for such service may be selected by the rate keys in the same manner as though a certain definite fixed rate were to be charged the subscriber A for any service rendered him. The closure of the rate key referred to does not complete the energizing circuit of the magnet 80, since at this time the supervisory relay 31 is deenergized and its armature is resting upon its back contact. In response to the request of the subscriber A, the operator inserts the plug P¹ in the jack J¹ of the subscriber B, who is to be called, and by depressing her ringing key K² in the manner well known in the art connects the ringing generator 46 with the line conductors 18 and 19, thus causing current to flow through the ringer located at the substation of the subscriber B. At this time the cut-off relay associated with the line conductors 18 and 19 has been energized, as already described for the relay 12, and thus connection between the battery 13 and the line wires 18 and 19 through the armatures of the cut-off relay is interrupted. When the subscriber B responds by removing his receiver from the hook switch, the circuit through the supervisory relays 31 and 32 is closed as follows: battery 13, wire 16, wire 39, wire 38, spring 36, spring 34, winding of supervisory relay 32, wire 30, sleeve strand 25, sleeve spring 21, line wire 19, substation apparatus of subscriber B, line wire 18, tip spring 20, tip strand 23, wire 29, winding of supervisory relay 31, spring 33, spring 35, wire 37, wire 28, wire 14, back to battery 13. The energization of the relay 31 completes the energizing circuit of the

magnet 80 as follows: battery 13, wire 16, wire 39, wire 38, wire 125, armature of relay 31, contact 50, wire 51, through the springs of the rate switch which has been actuated and through its associated commutator to the shaft 73, spring 79, winding of magnet 80, wire 81, wire 37, wire 28, wire 14, back to battery 13. The circuit just traced is closed at intervals, the duration of which is determined by the commutator connected in circuit and the rate of its rotation, as a result of which the magnet 80 is energized repeatedly at a rate depending upon the charge to be made to the subscriber A for the connection. Each actuation of the magnet 80 operates to advance the shaft 87 one step, as described above, and thus to move the nut 96 to the right by the rotation of the shaft 94 against the action of the spring 98, the pawl 88 serving to hold the shaft 87 and parts driven thereby in the position to which they are advanced. This condition continues either until the subscriber B hangs up his receiver, which by deenergizing the supervisory relay 31 opens the energizing circuit of the magnet 80 above traced, or by the withdrawal of the plug P¹ from the jack J¹ by the operator, which serves a similar purpose. The disconnect signals having been received by the operator in the usual manner, the plugs P and P¹ are withdrawn and the plug P¹ is inserted in the jack J, the subscriber A is called in the usual manner and upon his response he is asked to leave his receiver 2 in its removed position from the hook switch 3 a sufficient length of time so that the charge for the connection just terminated may be added to his meter 6. At this time the registering mechanism at the exchange is in a position such that by means of a scale 126 associated with the nut 96 the amount of charge may be read and noted if desired. After the operator has requested that the receiver 2 be left in its removed position as described, she depresses the key K, thus interrupting the circuit from the battery 13 through the supervisory relays 31 and 32 to the plug P¹ and closing a circuit as follows: battery 13, wire 14, wire 28, contact 118, contact 109, wire 108, spring 103, spring 113, wire 45, energizing winding of magnet 44, wire 42, spring 40, spring 33, energizing winding of the supervisory relay 31, wire 29, tip strand 23, tip spring 9, line wire 8, switch hook 3, transmitter 1, coil 5, line wire 7, sleeve spring 10, sleeve strand 25, wire 30, energizing winding of relay 32, spring 34, spring 41, wire 43, contact 114, contact 104, wire 38, wire 39, wire 16, back to battery 13. As a result of the circuit just traced the magnet 44 is energized and the pawl 88 is removed from engagement with the ratchet wheel 86, thus permitting the spring 98 to rotate the shaft 94 and parts carried thereby in the opposite direction to

the motion imparted to them by the operating pawl 84, this rotation being effected by means of the pawl 99 and the ratchet wheel 100. Thus the stud 101 is rotated and at 5 each rotation engages the cam 102, which serves to move the springs 103 and 104 from engagement with the springs 113 and 114 and into engagement with the springs 115 and 116. It is to be noted that the springs 10 103 and 104 are connected with the terminals of the battery 13 as long as the contacts 109 and 118 are closed and that, since the springs 114 and 115 are connected together and also since the springs 113 and 116 are connected 15 together, the alternate position of the switch K¹ serves to reverse the direction of current flow through the circuit above traced, thus serving to reverse the current through the coil 5 to actuate the registering mechanism 20 at the substation A. It is apparent that the mechanism employed at the exchange for sending the charge registered upon the scale 126 back into the calling subscriber's meter may be so designed as to operate at 25 the maximum rapidity which practical conditions upon the line circuit will permit, and that therefore a comparatively short space of time is required in which to transmit from the exchange to the subscriber's 30 meter a comparatively long conversation and therefore a comparatively high total charge. The mechanism that may be employed to properly limit the rate of rotation of the shafts 87 and 94 under the action of 35 the spring 99 is not here shown, since any well known escapement mechanism may be employed for this purpose. When the charge has been wholly transferred to the meter 6, the nut 96 is in its left-hand or 40 normal position and the contacts 109 and 118 are separated, thus opening the circuit through the magnet 44, as a result of which the pawl 88 is released and under the action of the spring 90 again engages the ratchet 45 wheel 86. If the subscriber A hangs up his receiver before the charge registered by the shaft 94 has been wholly transferred into the meter 6, the energizing circuit of the electromagnet 44 is interrupted as is the 50 energizing circuit of the supervisory relay 31, and the pilot lamp 111 is lighted by current flowing over the following circuit: battery 13, wire 14, wire 28, wire 37, contact 118, contact 109, wire 108, wire 106, armature 107, contact 112, lamp 111, wire 110, wire 38, wire 39, wire 16, back to battery 13. The deenergization of the relay 31 serves to light the lamp 49 over the following circuit: 55 battery 13, wire 14, wire 28, wire 37, wire 127, armature of relay 32, contact 48, lamp 49, contact 47, armature of relay 31, wire 125, wire 38, wire 39, wire 16, back to battery 13. The operator, by the simultaneous lighting of the lamps 49 and 111, is thus 60 advised that the receiver 2 has been pre- 65 mately placed upon the hook 3 and a second request may be made of the subscriber A to remove his receiver so that the charge may be properly added to his metering mechanism 6. If, on the other hand, the receiver 2 is not replaced until the entire charge has been added to the metering mechanism 6, the energizing circuits through the relay 31 and the magnet 44 are opened by the separation of the contacts 109 and 118, and since the circuit of the pilot lamp 111 is closed through these contacts when the magnet 44 is deenergized, the lamp 111 is not at this time lighted but the lamp 49 is lighted, thus advising the operator that the charge has been wholly transferred to the metering mechanism 6 and that the connection may be taken down. 70 75 80 85 90 95 100 105 110 115 120 125 130

While I have shown the particular mechanism above described for carrying out my invention, I do not, however, limit myself to this construction, but may employ any equivalent devices that are known in the art for accomplishing the same result.

What I claim is:

1. In a telephone system, the combination of an exchange, substations connected by line conductors with the exchange, mechanism at the exchange for connecting the lines for conversation, and means associated with the connecting mechanism for registering at the exchange the charge for a conversation at a desired one of a plurality of rates.
2. In a telephone system, the combination of an exchange, and mechanism at the exchange for registering at such exchange the charge for a talking connection established at the exchange at a desired one of a plurality of rates.
3. In a telephone system, the combination of an exchange, substations connected by line conductors with the exchange, mechanism at the exchange for connecting the lines for conversation, means associated with the connecting mechanism for registering the charge for a conversation at a desired one of a plurality of rates, a meter at one of the substations, and means for transferring the charge from the exchange to the meter.
4. In a telephone system, the combination of an exchange, substations connected by line conductors with the exchange, mechanism at the exchange for connecting the lines for conversation, means associated with the connecting mechanism for registering the charge for a conversation at a desired one of a plurality of rates, a meter at one of the substations, and means for transferring the charge from the exchange to the meter more rapidly than the charge was registered at the exchange.
5. In a telephone system, the combination of an exchange, mechanism at the exchange for registering the charge for a talking connection established at the exchange at a de

sired one of a plurality of rates, and means for sending from the exchange over a desired connection the charge thus registered and for returning the registering mechanism to its normal or zero condition.

6. In a telephone system, the combination of an exchange, substations connected by line conductors with the exchange, mechanism at the exchange for connecting the lines for conversation, means associated with the connecting mechanism for registering the charge for a conversation at a desired one of a plurality of rates, a meter at one of the substations, and means for transferring the charge from the exchange to the meter and for returning the registering means at the exchange to its normal or zero condition.

7. In a telephone system, the combination of an exchange, substations connected by line conductors with the exchange, mechanism at the exchange for connecting the lines for conversation, means associated with the connecting mechanism for registering the charge for a conversation, a meter at one of the substations, and means for transferring the charge from the exchange to the meter.

8. In a telephone exchange system, the combination of telephone lines extending from substations to an exchange, switching mechanism at the exchange for connecting the lines for conversation as desired, and a circuit independent of the talking circuit through the connected lines and controlled by such talking circuit, such independent circuit including an operating key and telechrone registering mechanism.

9. In a telephone exchange system, the combination of telephone lines extending from substations to an exchange, switching mechanism at the exchange for connecting the lines for conversation as desired, a circuit independent of the talking circuit through the connected lines and controlled by such talking circuit, such independent circuit including an operating key and telechrone registering mechanism, a meter at one of the substations, and means for transferring the charge from the exchange to the meter.

10. In a telephone exchange system, the combination of telephone lines extending from substations to an exchange, switching mechanism at the exchange for connecting the lines for conversation as desired, a circuit independent of the talking circuit through the connected lines and controlled by such talking circuit, such independent circuit including an operating key and telechrone registering mechanism, a meter at one of the substations, and means for transferring the charge from the exchange to the meter and for returning the registering mechanism to its normal or zero condition.

11. In a telephone exchange system, the combination of telephone lines extending from substations to an exchange, switching

mechanism at the exchange for connecting the lines for conversation as desired, a relay in the circuit thus established, a registering circuit closed by energization of such relay, and telechrone registering mechanism operated by the registering circuit when closed.

12. In a telephone exchange system, the combination of telephone lines extending from substations to an exchange, switching mechanism at the exchange for connecting the lines for conversation as desired, a circuit independent of the talking circuit through the connected lines and controlled by such talking circuit, such independent circuit including an operating key and telechrone registering mechanism, a meter at one of the substations, a charge-sending circuit at the exchange completed through a line connected with the switching mechanism and controlled by the continuity of such line circuit, and devices for transferring to the substation meter over the sending circuit the charge registered upon the telechrone registering mechanism.

13. In a telephone exchange system, the combination of telephone lines extending from substations to an exchange, switching mechanism at the exchange for connecting the lines for conversation as desired, a relay in the circuit thus established, a registering circuit closed by energization of such relay, telechrone registering mechanism operated by the registering circuit when closed, a meter at one of the substations, a charge-sending circuit at the exchange completed through the line connected with such relay and controlled by the continuity of such line circuit, and devices associated with the registering mechanism for transferring to the substation meter over the sending circuit the charge registered upon the telechrone registering mechanism and simultaneously returning such registering mechanism to its normal or zero position.

14. In a telephone system, the combination of an exchange, substations connected by line conductors with the exchange, mechanism at the exchange for connecting the lines for conversation, and means associated with the connecting mechanism for registering the charge for a conversation at a desired one of a plurality of rates, such registering mechanism operative only when the apparatus at the called substation is in talking condition.

15. In a telephone system, the combination of an exchange, substations connected by line conductors with the exchange, mechanism at the exchange for connecting the lines for conversation, means associated with the connecting mechanism for registering the charge for a conversation at a desired one of a plurality of rates, a meter at one of the substations adapted to be actuated by reversed current impulses in the line, and means at the exchange for repeatedly reversing the direc-

tion of current flow in the line to transfer the charge from the register to the meter.

16. In a telephone exchange system, the combination of telephone lines extending from substations to an exchange, switching mechanism at the exchange for connecting the lines for conversation as desired, and a circuit independent of the talking circuit through the connected lines and controlled by such talking circuit, such independent circuit including an operating key and telechrone registering mechanism and operative only when the apparatus at the called substation is in talking condition.

15 17. In a telephone exchange system, the combination of telephone lines extending from substations to an exchange, switching mechanism at the exchange for connecting the lines for conversation as desired, and a circuit independent of the talking circuit through the connected lines and controlled by such talking circuit, such independent circuit including telechrone registering mechanism and a plurality of operating keys adapted to cause the operation of the registering mechanism at different rates.

18. In a telephone exchange system, the combination of telephone lines extending from substations to an exchange, switching mechanism at the exchange for connecting the lines for conversation as desired, and a circuit independent of the talking circuit through the connected lines and controlled by such talking circuit, such independent circuit including telechrone registering mechanism and a plurality of operating keys adapted to cause the operation of the registering mechanism at different rates, such keys so related that a depressed key is retained in operative position until released by the operation of a second key.

19. In a telephone exchange system, the combination of telephone lines extending from substations to an exchange, switching mechanism at the exchange for connecting the lines for conversation as desired, a circuit independent of the talking circuit through the connected lines and controlled by such talking circuit, such independent circuit including telechrone registering mechanism and a plurality of operating keys adapted to cause the operation of the registering mechanism at different rates, such keys so related that a depressed key is retained in operative position until released by the operation of a second key, a meter at one of the substations adapted to be actuated by reversed current impulses in the line, and means at the exchange for repeatedly reversing the direction of current flow in the line to transfer the charge from the register to the meter.

20. In a telephone exchange system, the combination of telephone lines extending from substations to an exchange, switching

mechanism at the exchange for connecting the lines for conversation as desired, a circuit independent of the talking circuit through the connected lines and controlled by such talking circuit, such independent circuit including telechrone registering mechanism and a plurality of operating keys adapted to cause the operation of the registering mechanism at different rates, such keys so related that a depressed key is retained in operative position until released by the operation of a second key, a meter at one of the substations adapted to be actuated by reversed current impulses in the line, means at the exchange for repeatedly reversing the direction of current flow in the line to transfer the charge from the register to the meter, and a charge-sending key adapted when depressed to complete the circuit of the current reversing means, the operation of such sending key serving to release a previously actuated rate key.

21. In a telephone system, the combination of an exchange, substations connected by line conductors with the exchange, mechanism at the exchange for connecting the lines for conversation, means associated with the connecting mechanism for registering the charge for a conversation at a desired one of a plurality of rates, and a signal for indicating the termination of the charging operation.

22. In a telephone system, the combination of an exchange, substations connected by line conductors with the exchange, mechanism at the exchange for connecting the lines for conversation, means associated with the connecting mechanism for registering the charge for a conversation at a desired one of a plurality of rates, a meter at one of the substations, means for transferring the charge from the exchange to the meter, and a signal for indicating the termination of the transferring operation.

23. In a telephone system, the combination of an exchange, substations connected by line conductors with the exchange, mechanism at the exchange for connecting the lines for conversation, means associated with the connecting mechanism for registering the charge for a conversation, a meter at one of the substations, means for transferring the charge from the exchange to the meter, and a signal for indicating the termination of the transferring operation.

24. In a telephone system, the combination of an exchange, substations connected by line conductors with the exchange, mechanism at the exchange for connecting the lines for conversation, means associated with the connecting mechanism for registering the charge for a conversation at a desired one of a plurality of rates, a meter at one of the substations, means for transferring the charge from the exchange to the meter,

- a signal for indicating the termination of the charging operation, and a second signal for indicating the termination of the transferring operation.
- 5 25. In a telephone exchange system, the combination of telephone lines extending from substations to an exchange, switching mechanism at the exchange for connecting the lines for conversation as desired, a circuit independent of the talking circuit through the connected lines and controlled by such talking circuit, such independent circuit including an operating key and telechrone registering mechanism, and a signal for indicating the termination of the telechrone registering operation.
- 10 26. In a telephone exchange system, the combination of telephone lines extending from substations to an exchange, switching mechanism at the exchange for connecting the lines for conversation as desired, a circuit independent of the talking circuit through the connected lines and controlled by such talking circuit, such independent circuit including an operating key and telechrone registering mechanism, a meter at one of the substations, a charge-sending circuit at the exchange completed through a line connected with the switching mechanism and controlled by the continuity of such line circuit, devices for transferring to the substation meter over the sending circuit the charge registered upon the telechrone registering mechanism, and a signal for
- 15 indicating the termination of the transferring operation.
- 20 27. In a telephone exchange system, the combination of telephone lines extending from substations to an exchange, switching mechanism at the exchange for connecting the lines for conversation as desired, a circuit independent of the talking circuit through the connected lines and controlled by such talking circuit, such independent circuit including an operating key and telechrone registering mechanism, a meter at one of the substations, a charge-sending circuit at the exchange completed through a line connected with the switching mechanism and controlled by the continuity of such line circuit, devices for transferring to the substation meter over the sending circuit the charge registered upon the telechrone registering mechanism, and a signal for
- 25 indicating the termination of the transferring operation.
- 30 28. In a telephone exchange system, the combination of telephone lines extending from substations to an exchange, switching mechanism at the exchange for connecting the lines for conversation as desired, a circuit independent of the talking circuit through the connected lines and controlled by such talking circuit, such independent circuit including an operating key and telechrone registering mechanism, a meter at one of the substations, a charge-sending circuit at the exchange completed through a line connected with the switching mechanism and controlled by the continuity of such line circuit, devices for transferring to the substation meter over the sending circuit the charge registered upon the telechrone registering mechanism, and a signal for
- 35 indicating the termination of the transferring operation.
- 40 29. In a telephone exchange system, the combination of telephone lines extending from substations to an exchange, a cord circuit at the exchange for connecting the lines for conversation as desired, a supervisory relay associated with the calling plug of the cord circuit adapted to be energized when the apparatus at the connected substation is in talking condition, telechrone registering mechanism, an actuating magnet for such mechanism, an energizing circuit for such magnet closed through a make-contact on such relay, and a commutator for interrupting such energizing circuit at a rate proportionate to the charge rate for the connection effected.
- 45 30. In a telephone exchange system, the combination of telephone lines extending from substations to an exchange, a cord circuit at the exchange for connecting the lines for conversation as desired, a supervisory relay associated with the calling plug of the cord circuit adapted to be energized when the apparatus at the connected substation is in talking condition, telechrone registering mechanism, an actuating magnet for such mechanism, an energizing circuit for such magnet closed through a make-contact on such relay, a plurality of commutators associated with the energizing circuit and adapted to send current impulses therethrough at rates proportionate to the rates charged for different connections, and selective keys adapted to connect a desired one of such commutators in the energizing circuit.
- 50 31. In a telephone exchange system, the combination of telephone lines extending from substations to an exchange, a cord circuit at the exchange for connecting the lines for conversation as desired, a supervisory relay associated with the calling plug of the cord circuit adapted to be energized when the apparatus at the connected substation is in talking condition, telechrone registering mechanism, an actuating magnet for such mechanism, an energizing circuit for such magnet closed through a make-contact on
- 55 60 65 70 75 80 85 90 95 100 105 110 115 120 125 130

such relay, a plurality of commutators associated with the energizing circuit and adapted to send current impulses therethrough at rates proportionate to the rates charged for different connections, selective keys adapted to connect a desired one of such commutators in the energizing circuit, and interlocking mechanism for retaining an actuated key in its operated position and releasing a previously actuated key.

32. In a telephone exchange system, the combination of telephone lines extending from substations to an exchange, a cord circuit at the exchange for connecting the lines for conversation as desired, a supervisory relay associated with the calling plug of the cord circuit adapted to be energized when the apparatus at the connected substation is in talking condition, telechrone registering mechanism, ratchet devices for effecting a step-by-step actuation of such mechanism, a magnet for operating such devices, an energizing circuit for such magnet closed through a make-contact on such relay and thereby under the control of the connected subscriber, a plurality of commutators associated with the energizing circuit and adapted to send current impulses therethrough at rates proportionate to the rates charged for different connections, selective keys adapted to connect a desired one of such commutators in the energizing circuit, and interlocking mechanism for retaining an actuated key in its operated position and releasing a previously actuated key.

33. In a telephone exchange system, the combination of telephone lines extending from substations to an exchange, a cord circuit at the exchange for connecting the lines for conversation as desired, a supervisory relay associated with the calling plug of the cord circuit adapted to be energized when the apparatus at the connected substation is in talking condition, telechrone registering mechanism, a meter at one of the substations adapted to be operated by current impulses sent over the associated line circuit, impulse sending mechanism associated with the registering mechanism, and a key adapted by its operation to include the impulse sending mechanism in the energizing circuit of such relay.

34. In a telephone exchange system, the combination of telephone lines extending from substations to an exchange, a cord circuit at the exchange for connecting the lines for conversation as desired, a supervisory relay associated with the calling plug of the cord circuit adapted to be energized when the apparatus at the connected substation is in talking condition, telechrone registering mechanism, an actuating magnet for such mechanism, an energizing circuit for such magnet closed through a make-contact on such relay, a holding device for the register-

ing mechanism, motor mechanism operated by the actuating magnet, a meter at one of the substations adapted to be operated by current impulses sent over the associated line alternately in reversed direction, a reversing switch operated by the motor mechanism, and a key adapted by its operation to include the reversing switch in the energizing circuit of such relay and to release the holding device to permit operation of the motor mechanism.

35. In a telephone exchange system, the combination of telephone lines extending from substations to an exchange, a cord circuit at the exchange for connecting the lines for conversation as desired, a supervisory relay associated with the calling plug of the cord circuit adapted to be energized when the apparatus at the connected substation is in talking condition, telechrone registering mechanism, an actuating magnet for such mechanism, an energizing circuit for such magnet closed through a make-contact on such relay, a holding pawl for the registering mechanism, a releasing magnet for such pawl, motor mechanism connected with the registering mechanism and placed in driving condition by the registering operation, a polarized meter at one of the substations adapted to be operated by alternating current impulses sent over the line circuit, a reversing switch operable by the registering mechanism only in a clearing direction, and a key adapted by its operation to include the releasing magnet and reversing switch in the energizing circuit of such relay.

36. In a telephone exchange system, the combination of telephone lines extending from substations to an exchange, a cord circuit at the exchange for connecting the lines for conversation as desired, a supervisory relay associated with the calling plug of the cord circuit adapted to be energized when the apparatus at the connected substation is in talking condition, telechrone registering mechanism, an actuating magnet for such mechanism, an energizing circuit for such magnet closed through a make-contact on such relay, a holding pawl for the registering mechanism, a releasing magnet for such pawl, motor mechanism connected with the registering mechanism and placed in driving condition by the registering operation, a polarized meter at one of the substations adapted to be operated by alternating current impulses sent over the line circuit, a reversing switch operable by the registering mechanism only in a clearing direction, a key adapted by its operation to include the releasing magnet and reversing switch in the energizing circuit of such relay, and a switch for opening the relay energizing circuit when the charge registered has been transferred to the meter.

37. In a telephone exchange system, the

- combination of telephone lines extending from substations to an exchange, a cord circuit at the exchange for connecting the lines for conversation as desired, a supervisory relay associated with the calling plug of the cord circuit adapted to be energized when the apparatus at the connected substation is in talking condition, telechrone registering mechanism, a meter at one of the substations 5 adapted to be operated by current impulses sent over the associated line circuit, impulse sending mechanism associated with the registering mechanism; a key adapted by its operation to include the impulse sending mechanism in the energizing circuit of such relay, and a signal for indicating the opening of the line circuit before the end of the charge transferring operation.
38. In a telephone exchange system, the 20 combination of telephone lines extending from substations to an exchange, a cord circuit at the exchange for connecting the lines for conversation as desired, a supervisory relay associated with the calling plug of the 25 cord circuit adapted to be energized when the apparatus at the connected substation is in talking condition, telechrone registering mechanism, an actuating magnet for such mechanism, an energizing circuit for such 30 magnet closed through a make-contact on such relay, a holding pawl for the registering mechanism, a releasing magnet for such pawl, motor mechanism connected with the registering mechanism and placed in driving condition by the registering operation, a 35 polarized meter at one of the substations adapted to be operated by alternating current impulses sent over the line circuit, a reversing switch operable by the registering mechanism only in a clearing direction, a 40 key adapted by its operation to include the releasing magnet and reversing switch in the energizing circuit of such relay, a switch for opening the relay energizing circuit 45 when the charge registered has been transferred to the meter, and an electric lamp to signal controlled by the releasing magnet to indicate the premature opening of the charge sending circuit.
50. 39. In a telephone exchange system, the combination of telephone lines extending from substations to an exchange, a cord circuit at the exchange for connecting the lines for conversation as desired, a supervisory 55 relay associated with the calling plug of the cord circuit adapted to be energized when the apparatus at the connected substation is in talking condition, telechrone registering mechanism, an actuating magnet for such 60 mechanism, an energizing circuit for such magnet closed through make-contacts on such relay, a commutator for interrupting such energizing circuit at a rate proportionate to the charge rate for the connection
- effected, and a signal for indicating the termination of the charging operation.
40. In a telephone exchange system, the combination of telephone lines extending from substations to an exchange, a cord circuit at the exchange for connecting the lines 70 for conversation as desired, a supervisory relay associated with the calling plug of the cord circuit adapted to be energized when the apparatus at the connected substation is in talking condition, telechrone registering 75 mechanism, an actuating magnet for such mechanism, an energizing circuit for such magnet closed through a make-contact on such relay, a commutator for interrupting such energizing circuit at a rate proportionate to the charge rate for the connection 80 effected, a meter at one of the substations adapted to be operated by current impulses sent over the associated line circuit, impulse 85 sending mechanism associated with the registering mechanism, and a key adapted by its operation to include the impulse sending mechanism in the energizing circuit of such relay.
41. In a telephone exchange system, the 90 combination of telephone lines extending from substations to an exchange, a cord circuit at the exchange for connecting the lines for conversation as desired, a supervisory relay associated with the calling plug 95 of the cord circuit adapted to be energized when the apparatus at the connected substation is in talking condition, telechrone registering mechanism, an actuating magnet for such mechanism, an energizing circuit 100 for such magnet closed through a make-contact on such relay, a plurality of commutators associated with the energizing circuit and adapted to send current impulses therethrough at rates proportionate to the rates 105 charged for different connections, selective keys adapted to connect a desired one of such commutators in the energizing circuit, a holding device for the registering mechanism, motor mechanism operated by the actuating magnet, a meter at one of the substations adapted to be operated by current impulses sent over the associated line alternately in reversed direction, a reversing 110 switch operated by the motor mechanism, and a key adapted by its operation to include the reversing switch in the energizing circuit 115 of such relay and to release the holding device to permit operation of the motor mechanism, such last-named key when actuated being retained in operated position and serving to release a previously actuated selective key.
42. In a telephone exchange system, the combination of telephone lines extending from substations to an exchange, a cord circuit at the exchange for connecting the lines for conversation as desired, a supervisory 120 relay associated with the calling plug of the

cord circuit adapted to be energized when the apparatus at the connected substation is in talking condition, telechrone registering mechanism, ratchet devices for effecting a 5 step-by-step actuation of such mechanism, a magnet for operating such devices, an energizing circuit for such magnet closed through a make-contact on such relay and thereby under the control of the connected 10 subscriber, a plurality of commutators associated with the energizing circuit and adapted to send current impulses therethrough at rates proportionate to the rates charged for different connections, selective keys adapted 15 to connect a desired one of such commutators in the energizing circuit, interlocking mechanism for retaining an actuated key in its operated position and releasing a previously actuated key, a holding pawl for the registering 20 mechanism, a releasing magnet for

such pawl, motor mechanism connected with the registering mechanism and placed in driving condition by the registering operation, a polarized meter at one of the substations adapted to be operated by alternating 25 current impulses sent over the line circuit, a reversing switch operable by the registering mechanism only in a clearing direction, a key adapted by its operation to include the releasing magnet and reversing switch in 30 the energizing circuit of such relay, a switch for opening the relay energizing circuit when the charge registered has been transferred to the meter, and a signal for indicating the opening of the line circuit before 35 the end of the charge transferring operation.
